UNITED STATES PATENT OFFICE.

FRANK DI IANNI, OF BROOKLYN, NEW YORK, ASSIGNOR TO AMERICAN MACHINE AND FOUNDRY COMPANY, A CORPORATION OF NEW JERSEY.

MOUNT FOR THE TONGUES OF CIGARETTE-ROD-FORMING MECHANISM.

Application filed June 5, 1926. Serial No. 113,952.

This invention relates to an improved mount for the tongue of a cigarette rod-forming mechanism.

In the operation of the present day high-speed cigarette machines, the continuous smooth running of the cigarette rod being formed depends to a considerable extent on the accurate adjustment of the tongue in the rod-forming mechanism, which adjustment, after being made for prevailing conditions, should remain constant during the entire machine run. But fine particles of dirt or tobacco sometimes work their way in between the tongue and tapered tube of the rod-forming mechanism and tear the extremely thin paper or choke the mechanism, or both. Such obstructions must be cleared away before operation of the machine can proceed. In order to do this, it is necessary to remove the tongue to open the rod-forming mechanism and enable the machine operator to get at the obstruction. Heretofore, when this occurred, the machine operator did not always replace the tongue in its proper place in the rod-forming mechanism, and as a result of the misplacement of the tongue, the machine did not operate as smoothly as before. It is the main object of the present invention to provide a mount for the tongue of a cigarette rod-forming mechanism which is readily adjustable in great accuracy, and from which the tongue may be demounted and on which the tongue may be remounted, without disturbing the accurate adjustment of the mount, in order to cure the existing defect of cigarette machines above pointed out. With this and other objects not specifically mentioned in view, the invention consists in certain constructions and combinations which will be hereinafter fully described and then specifically set forth in the claims hereunto appended.

In the accompanying drawings, in which like characters of reference indicate the same or like parts, Fig. 1 is a plan view of a mount constructed in accordance with the invention; Fig. 2 is a side elevation of the structure shown in Fig. 1; Fig. 3 is a sectional end elevation of the adjusting device, taken on the line 3—3 in Figs. 1 and 2;

Fig. 4 is an enlarged side elevation of the adjusting device; and Fig. 5 is an enlarged end elevation of the same.

In carrying the invention into effect, there is provided a mount for the tongue of a cigarette rod-forming mechanism, comprising a support, means for adjusting said support to control the position of the tongue in said mechanism, and a device for demountably attaching said tongue to the adjusted support, so that the tongue may be removed to open the rod-forming mechanism and permit the removal therefrom of obstructions, and may be replaced after removal of said obstructions, without disturbing the accurate adjustment of the support which is necessary to high machine output. Changes and variations may be made in the construction of these parts within the scope of the claims. The invention, therefore, is not to be restricted to the precise details of the structure shown and described.

Referring to the drawings, the adjustable tongue 6 coacts in the usual manner with the stationary tube 7 supported on the frame of the machine. The tongue is located between the guide plates 8, 8, which are fastened to the tube 7 by screws 9. The tongue 6 and tube 7 are both nearly as broad as the cigarette wrapper at their receiving ends, and the size of the finished cigarette at their delivery ends. The wrapper 10, with the tobacco 11 evenly distributed on it, is carried by the tape 12 through the rod-forming mechanism 6—7—12, the bore of which gradually and progressively folds the wrapper around the tobacco in the usual manner so as to deliver it in the form of a rod 13 to the sealer-guide 14.

In entering the rod-forming mechanism, the wrapper 10 passes over a roller 15 carried by a pivoted frame 16 which, by means of a worm 17 turnable by means of the knob 18, can be adjusted so as to properly guide the wrapper into the rod-forming mechanism.

The tongue 6, near its receiving end, is provided with a bracket 19 which, by means of the screw 20, is attached to one of the guide plates 8. Near its delivery end, the tongue is provided with a web 21 by means

of which it is demountably attached to its mount which is carried by one of the guide plates 8 forming a part of the rod-forming mechanism.

- 5 In the frame 22 of the mount for the tongue, a block 23 is vertical slidable. This block carries a horizontal stem 24 which is slidable therein, and to the end of which the web 21 of the tongue 6 is demountably attached by means of the screw 25. One end of the stem 24 is provided with a collar 26 and a spring 27, the latter thrusting against the collar 26 and the block 23. The other end of the stem 24 carries the adjusting nut 28. Operation of this nut and the opposing spring 27 produces longitudinal movement of the stem 24, thereby laterally or horizontally adjusting the tongue 6.

For the vertical adjustment of the tongue, 20 the frame 22 has an adjusting screw 29 bearing against the block 23, and an opposing spring 30 pressing against the opposite side of the block. Guidepins 31, inserted in the block 23, prevent horizontal movement 25 thereof and keep the block in alignment with the frame 22.

In order to keep the adjusted mount locked in any position to which it is moved, the heads of the nut 28 and screw 29 are 30 serrated, and into the serrations snaps the point on the free ends of flat springs 32 and 33, respectively, as the heads are turned in either direction. These lock-springs also afford means for holding the mount in finely adjusted position.

The tongue web 21 is slotted at 34 for sliding engagement with the stem 24 in demounting and remounting.

The tongue, once properly adjusted for given conditions, can be removed by simply loosening the screws 20 and 25 and withdrawing it from the tube 7. When it is replaced, and the screws again tightened, it will then again be in the exact adjusted position from which it was withdrawn. Thus, the tongue may be repeatedly removed and replaced without disturbing the accurate adjustment of the mount.

What is claimed is:

- 50 1. A mount for the tongue of a cigarette rod-forming mechanism, comprising a support, means for adjusting said support both vertically and horizontally to control the position of the tongue in said mechanism, and a device for demountably attaching said tongue to the adjusted support.
- 55 2. A mount for the tongue of a cigarette rod-forming mechanism, comprising a support, means for adjusting said support both vertically and horizontally to control the position of the tongue in said mechanism, and a device for demountably attaching said tongue to the adjusted support, said support including operative connections and a stem engaging said tongue.

3. A mount for the tongue of a cigarette rod-forming mechanism, comprising a support, means for adjusting said support both vertically and horizontally to control the position of the tongue in said mechanism, and a device for demountably attaching said tongue to the adjusted support, said support including operative connections and a laterally movable stem engaging said tongue.

4. A mount for the tongue of a cigarette rod-forming mechanism, comprising a support, means for adjusting said support both vertically and horizontally to control the position of the tongue in said mechanism, and a device for demountably attaching said tongue to the adjusted support, said support including operative connections, a stem engaging said tongue, and a block engaging said stem.

5. A mount for the tongue of a cigarette rod-forming mechanism, comprising a support, means for adjusting said support to control the position of the tongue in said mechanism, and a device for demountably attaching said tongue to the adjusted support, said support including operative connections, a laterally movable stem engaging said tongue, and a vertically movable block engaging said stem.

6. A mount for the tongue of a cigarette rod-forming mechanism, comprising a support, means for adjusting said support to control the position of the tongue in said mechanism, and a device for demountably attaching said tongue to the adjusted support, said support including a laterally movable stem engaging said tongue, a vertically movable block engaging said stem, and a frame carried by said mechanism and engaging said block.

7. A mount for the tongue of a cigarette rod-forming mechanism, comprising a support, means for adjusting said support to control the position of the tongue in said mechanism, and a device for demountably attaching said tongue to the adjusted support, said means including screws and opposing springs for holding said support in adjusted position.

8. A mount for the tongue of a cigarette rod-forming mechanism, comprising a support, means for adjusting said support to control the position of the tongue in said mechanism, and a device for demountably attaching said tongue to the adjusted support, said means including screws and opposing springs operative in different directions for holding said support in adjusted position.

9. A mount for the tongue of a cigarette rod-forming mechanism, comprising a support, means for adjusting said support to control the position of the tongue in said mechanism, and a device for demountably attaching said tongue to the adjusted sup-

port, said support including a stem having a collar engaging said tongue, and said device including a screw threaded into said stem and holding said tongue against said collar.

5 10. A mount for the tongue of a cigarette rod-forming mechanism, comprising a support, means for adjusting said support to control the position of the tongue in said mechanism, and a device for demountably

attaching said tongue to the adjusted support, said tongue having an open slot, said support having a stem engaging said tongue, and said device being operative to clamp said tongue on said stem. ¹⁰

In testimony whereof, I have signed my ¹⁵ name to this specification.

FRANK DI IANNI.
